JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

PICKER-STICK CHECK FOR LOOMS.

Application filed August 16, 1921. Serial No. 492,732.

To all whom it may concern:

Be it known that I, JONAS NORTHRUP, a citizen of the United States, residing at Hopedale, in the county of Worcester and State of Massachusetts, have invented certain new and useful Improvements in Picker-Stick Checks for Looms; and I do hereby declare the following to be a full, clear, and exact description of the invention, such as will enable others skilled in the art to which it appertains to make and use the same.

The present invention relates to an improvement in picker stick checks for looms.

The object of the invention is to reorganize and improve picker stick checks, particularly with the object of checking and stopping the shuttle in an efficient manner, and providing means for regulating its action as the parts wear in use. To this end the invention consists in the picker stick check hereinafter described and particularly defined in the claims.

In the accompanying drawings illustrating the preferred form of the invention, Fig. 1 is a front elevation of the check; Fig. 2 is an enlarged view of the female member of the check; and Fig. 3 is a plan view of the male member.

The illustrated embodiment of the invention is described as follows: The lay beam 1 is provided with the usual box 2 and picker stick slot, through which the picker stick 3 extends, being provided upon its upper end with a shuttle check 4. To the lay is attached a bracket 5, provided with a male member carrying arm 6. The female member of the picker stick check is indicated in a general way by the reference character 7, and consists of a base 8, consisting of an angle bar secured to the staff. Mounted on the angle bar is the loop 9 which consists of a rectangular piece of metal having feet 10, by which it is secured to the angle bar 8. The loop is lined upon opposite sides with friction leather 11, between which the male member, indicated in a general way by the reference character 20, is received. The female member is secured to the staff by means of the clip 12, which embraces the staff by means of its bolt 13, and securely attaches the female member thereto.

The male member of the picker stick check consists of the angle member 21, which is the male member support, having a foot 22

arranged at right angles to the portion 21, which is slotted at 23 to receive the bolt 24, by which the member is secured to the male member supporting portion 6 of the bracket 5 in adjusted position. At the end 60 of the member 21 are attached two leather covered spring members 25, being riveted thereto at 26. The rear ends of the spring members 25 are received between the two nuts 27 supported on the adjusting screw 28. The adjusting screw passes through a hole in the member 21, and is held from endwise movement with relation thereto by means of a collar 29 secured to the adjusting screw 28, which abuts against one side 70 of the member 21 and on the other side by means of a washer 30 held in place by a cotter pin 31, between which washer and member 21 is interposed a spring wire 32, which is wound one or more times around 75 the adjusting screw and has its two ends extended in opposite directions, lying against the foot 22 of the male member support 21. The spring 32 causes the collar 29 to bear with sufficient pressure upon the 80 male member support 21 to hold it from accidental rotation with relation thereto. The adjusting screw 28 is provided with a right-hand thread on one end and a left-hand thread on the other, which engage the two 85 adjusting nuts 27 respectively. The arrangement is such that by turning the adjusting screw 28, the free ends of the spring members 25 may be drawn closer together, or permitted to expand farther apart, so 90 that the resistance offered to the impalement of the female member on the male may be adjusted to such an amount as to arrest the motion of the shuttle effectively without subjecting the parts to shock, and to eliminate the rebound of the shuttle.

In automatic weft replenishing looms, and particularly in such looms wherein the condition of critical exhaustion of the filling is determined by a feeler, it is important that 100 the shuttle should be boxed at a precise position in the shuttle box so that the feeler may enter through the slot in the shuttle and engage always the same portion of the bobbin. By means of the adjustment of the 105 picker stick check provided by the present construction, the shuttle may be boxed in a precise position, and the position of the shuttle may be maintained by adjustment of the check as wear of the check advances by 110

allowing the spring members of the check to expand a slightly greater distance to compensate for the enlargement in size of the female member and the reduction in size of the male member. Thus, when the attachment is first applied to a loom, the adjustment will be made so as to stop the shuttle in correct position. As wear advances, the adjusting screw will be turned to move 10 the nuts 27 slightly farther outward, so as to maintain the position of stopping of the shuttle.

It will be observed that the female member may be easily removed from the picker stick staff by loosening the clip 12 and dropping it on the staff, and taking off the member which can be easily replaced by a new one. It will also be observed that the male member may be adjusted longitudinally of 15 the male member supporting portion of the bracket, correctly to position the male member with relation to the picker stick staff by loosening the bolt 24 and moving it backward and forward until it is centered with 20 relation to the female member on the picker stick staff. It will also be observed that the male member may be moved in its entirety by removing the bolt 24, and a new male member put in place and adjusted in secured 25 position by the same bolt. The male member supporting portion of the bracket 5 is channeled, and it receives the foot 22 and both of the ends 27 within the channel, so that the male member is rigidly supported in correct position with relation to 30 the picker stick staff. It is also to be noted that the picker stick check bracket 5 is longitudinally adjustable upon the lay, being secured thereto by a bolt which passes 35 from an elongated slot in the foot of the bracket 5, which engages the rear side of the lay. The bracket is not liable to displacement on the lay by reason of the fact that it is provided with two lugs which engage 40 the under side of the lay and together with the bolt hold the bracket from turning.

Having thus described the invention, what is claimed is:

1. A picker stick check for looms having, 50 in combination, male and female members, the one adapted to be secured to the picker stick staff, and the other to the lay, one of the members being provided with means for adjustment of its size, so as to determine 55 the position of stopping of the picker staff and shuttle.

2. A picker stick check for looms having, in combination, male and female members, one member being attached to the picker stick staff and the other to the lay, the male 60 member comprising a male member support and two spring members attached thereto, and means for adjusting the outward position of the free ends of the spring members.

3. A picker stick check for looms having, in combination, a female member consisting of a frame provided with parallel friction material lined sides attached to the picker stick staff, a male member comprising a 70 male member support attached to the lay and having two spring members attached at their ends to the male member support, and means for limiting the outward positions of the spring members.

4. A picker stick check for looms having in combination, a female member having an elongated vertical opening attached to the picker stick staff, a male member, comprising a male member support having spring members attached on its end adapted to enter the opening in the female member and to press outwardly against the walls thereof, said male member support having a foot secured to the lay, and adjusting means for 80 adjusting the outward position of the spring members, having a friction device for holding it from rotation.

5. A picker stick check for looms having, in combination, a female member consisting of an angle bar and loop attached to the side thereof, and a clip for securing it to the picker stick staff, a male member provided with a resilient portion supported upon the lay and adapted to be compressed as 90 it enters the female member.

6. A picker stick check for looms having, in combination, male and female members, one being attached to the picker staff, a bracket for supporting the other member of the check, provided with a foot having portions engaging two adjacent surfaces of the lay.

7. A picker stick check for looms having, in combination, two friction members, one being attached to the picker stick staff, a bracket attached to the lay for supporting the other check member, said bracket being provided with a groove to receive the foot of said member to hold it in position.

JONAS NORTHRUP.
